UNITED STATES PATENT OFFICE.

FREDRIK LINDBLAD, OF NEW YORK, N. Y.

CAR-WHEEL.

1,023,574.

Specification of Letters Patent. Patented Apr. 16, 1912.

Application filed October 25, 1911. Serial No. 656,617.

To all whom it may concern:

Be it known that I, FREDRIK LINDBLAD, a subject of the King of Sweden, and a resident of the city of New York, borough 6 of Manhattan, in the county and State of New York, have invented a new and Improved Car-Wheel, of which the following is a full, clear, and exact description.

Among the principal objects which the 10 present invention has in view are: to deaden the noise caused by the passage of metal carrying-wheels over metal rails; to provide a two-part carrying-wheel having a shoe separated from the body of the wheel 15 by suitable yielding cushions; to provide in a wheel of the character described, means for conducting electricity from the said shoe to the body of the wheel, to complete the electric circuit through the rail and 20 wheel.

Reference is to be had to the accompanying drawing forming a part of this specification, in which similar characters of reference denote corresponding parts in all the 25 views, and in which—

Figure 1 is a vertical section taken on the line 1—1 of Fig. 2; Fig. 2 is an outer face view of a car wheel constructed and arranged in accordance with the present invention; Fig. 3 is an outer face view of a 30 wheel constructed in accordance with the present invention, a bolting ring with which the wheel is provided being removed; Fig. 4 is a perspective view, in detail, of the 35 bolting ring for holding the separate parts of the wheel assembled; Fig. 5 is a detail view in side elevation, showing the construction of the body portion of the wheel; Fig. 6 is a detail view in side elevation, showing 40 the silencing pad employed in the present invention; Fig. 7 is a detail view in side elevation, of the wearing shoe employed in 45 wheels of this construction; and Fig. 8 shows the bolting ring for holding assembled the separable parts of the wheel.

As seen in the drawings, the wheel is provided with a heavy body portion 12, on which is formed a brake flange 13. The 50 brake flange 13 is preferably extended toward the center of the car for which the wheel is intended, or toward the center of the roadbed. Extended radially from the body 12 is a supporting flange 14. The 55 flange 14 is provided to form a backing for the vertical extension of the silencing pad employed, while the flange 15 with which

the body 12 is also provided supports the said pad in its horizontal disposition. As seen best in Fig. 5 of the drawings, the flange 15 is separated at intervals to form 60 channels 16, 16. The adjacent faces of the flanges 14 and 15 are machined to form the square rabbeted recesses, as seen best in Fig. 1 of the drawings.

The pad 17 is best seen in Fig. 6 of the 65 drawings. The pad is provided with horizontal segmental extensions 18, 18. The extensions 18 are designed to rest between the portions of the flange 15 and the shoe of the wheel. The extensions 18 are each provided at both ends thereof with radial projections 19. The projections 19 fit within the channels 16 when the pad 17 is fitted upon the body 12. The function of the projections 19 is to prevent the metallic contact 70 between the sides of the portions of the flange 15 and the sides of the lugs 20 with which the shoe is provided. The lugs 20, 20 extend between the projections 19, 19 into the channels 16, 16. The projections 75 19, 19 together with the lugs 20, 20, completely and snugly fill the channels 16, thereby securing a unity of construction and operation between the body and wearing 80 shoe of the wheel.

It is to secure the body 12, the pad 17 and the shoe 21 in their assembled relation that I provide the bolting ring 22. The ring 22 is provided with bolt-holes 23, 23, to register with bolt-holes 24, 24 formed in the flange 90 15, to press the shoe 21 against the vertical flange of the pad 17 and the flange 14. The ring 22 is also furnished with a series of pads 25. The pads 25 are shaped and aligned to extend between the projections 19 and to 95 rest upon the lugs 20, to force the said lugs and shoe 21 connected therewith against the pad 17 and the flange 14. The pads 25 are employed instead of metal lugs or projections, to avoid the transmission of the metallic vibration from the shoe 21 through the 100 ring 22 and the bolt securing the same to the body 12 of the wheel. When the ring 22 is thus positioned, the bolts 26 are placed in position and set up to draw the ring 22 105 securely home, when the wheel will be found structurally complete.

When the wheel is employed on vehicles driven by electric traction, I provide coiled-spring sections 27, to transmit the current 110 from the shoe 21 to the body 12 of the wheel. As seen best in Figs. 2 and 3 of the

drawings, the spring sections 27 are rigidly mounted upon the portions of the flange 15, to bridge the channels 16. When the lugs 20 of the shoe 21 are placed within the channels 16, it will be found that the coil of the spring sections 27 rests against the said lugs. The necessary metallic contact between the shoe 21 and the body of the wheel is thus formed without employing 10 an element which would transmit the metallic vibration from one to the other.

It will be understood that the pads 17, being more perishable than the body 12 and the shoe 21, will be replaced. For this 15 purpose, the operation is to remove the bolts 26 and the ring 22 held thereby, when the shoe 21 and the pad 17 may be removed and either or both substituted and the construction reassembled.

20 It will be observed that by means of this construction, a carrying-wheel is formed in which the traction sound or click and grind of the carrying wheels upon the rail is deadened.

25 Having thus described my invention, what I claim as new and desire to secure by Letters Patent is:—

1. A car wheel having a metal body portion provided with a horizontally extended 30 supporting flange, said flange having holding recesses formed therein; a flanged wearing shoe adapted for mounting upon said supporting flange, said shoe having lugs for disposition in said recesses; and an acoustic insulating material disposed between said shoe and the lugs thereof and said body portion and said recesses.

2. A car wheel having a metal body portion provided with a horizontally extended 40 supporting flange, said flange having holding recesses formed therein; a flanged wearing shoe adapted for mounting upon said supporting flange, said shoe having lugs for disposition in said recesses; and a sound 45 deadening pad shaped to fit between said body portion, said supporting flange, the sides of said recesses, and said wearing shoe and the lugs thereof.

3. A car wheel having a metal body portion and provided with a horizontally extended supporting flange, said flange having holding recesses formed therein; a metal wearing shoe adapted for mounting upon said flange and having lugs to extend within the recesses thereof; an acoustic insulating pad disposed between said body portion, said flange and said shoe; a bolting ring to hold said shoe in operative position; and a plurality of pads mounted on said ring to bear upon said lugs on said shoe. 60

4. A car wheel having a metal body portion and provided with a horizontally extended supporting flange, said flange having holding recesses formed therein; a metal wearing shoe adapted for mounting upon said flange and having lugs to extend within the recesses thereof; an acoustic insulating pad disposed between said body portion, said flange and said shoe; and a bolting ring adapted to be secured upon said body portion and having acoustic insulating pads mounted thereon to bear upon the lugs of said shoe. 65

5. A car wheel having a metal body portion and provided with a horizontally extended supporting flange, said flange having holding recesses formed therein; a metal wearing shoe adapted for mounting upon said flange and having lugs to extend within said recesses; an acoustic insulating pad disposed between said body portion, said flange, and said shoe; a bolting ring adapted to be secured upon said body portion and having acoustic insulating pads mounted thereon to bear upon the lugs of said shoe; 70 and a plurality of spiral springs rigidly mounted on said supporting flange to bear against said lugs to form electric circuit between said shoe and said body portion. 75

In testimony whereof I have signed my name to this specification in the presence of 90 two subscribing witnesses.

FREDRIK LINDBLAD.
